UNITED STATES PATENT OFFICE.

MORRIS F. LANGFELD, OF CHICAGO, ILLINOIS, ASSIGNOR TO HIMSELF AND DAVID HEIDELBERGER, OF SAME PLACE.

DESIGN FOR A SATCHEL.

SPECIFICATION forming part of Design No. 14,760, dated February 19, 1884.

Application filed November 19, 1883. Term of patent 3½ years.

To all whom it may concern.

Be it known that I, MORRIS F. LANGFELD, residing at Chicago, in the county of Cook and State of Illinois, and a citizen of the United States, have invented a new and useful Design for Ladies' Shopping-Satchels, of which the following is a full description, reference being had to the accompanying drawings, in which—

Figure 1 is an elevation of the front of a satchel; and Figs. 2 and 3, similar elevations, showing slight modifications which embrace the features of my design.

This design is adapted to be placed on or worked into the fronts or backs, or both, in

ladies' shopping satchels, wallets, or bags, 15 such as are carried by hand or suspended from a waist-belt, either for use or ornament; and it consists of the representation of a lacing, A, border-strips B, and fastenings D, arranged within the borders of the satchel. 20

What I claim is—

The design for ornamenting ladies' shopping-satchels, substantially as shown and described.

MORRIS F. LANGFELD
